UNITED STATES PATENT OFFICE.

FRANK C. HOBBS, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

POCKET-BILLIARD-TABLE POCKET.

1,174,153.

Specification of Letters Patent.

Patented Mar. 7, 1916.

Application filed May 13, 1915. Serial No. 27,835.

To all whom it may concern:

Be it known that I, FRANK C. HOBBS, a citizen of the United States, residing at Muskegon, in the county of Muskegon and 5 State of Michigan, have invented new and useful Improvements in Pocket-Billiard-Table Pockets, of which the following is a specification.

This invention relates to improvements in 10 pockets for pocket-billiard tables and its object is, broadly, to provide a sanitary pocket of strong but simple construction which will not permit the accumulation of dirt and other foreign matter and which 15 will at all times permit access to the interior of the pocket for cleaning or other purposes.

The pockets of pocket-billiard tables have usually been made of openwork leather or fabric material which permit the accumulation 20 of dust and dirt therein and which are difficult to clean. Furthermore, these pockets form convenient receptacles for dirt and dust which is brushed from the table in cleaning the same, and players oftentimes 25 shake ashes from their cigars and cigarettes and even throw the stubs of cigars and cigarettes into the pockets, rendering them dirty and unsanitary. It is a common occurrence for the chalk to fall into the pockets 30 and when the tables are provided with gullies it often happens that the chalk so deposited in the pockets will slide down into and choke the gully, making it necessary for an attendant to crawl under the table to remove the chalk. For these and other reasons 35 efforts have been made in the past to provide pockets from which the balls may be removed without inserting the hand into the pockets but my present invention is de-

40 signed to provide a strong and substantial openwork pocket of simple construction which will retain the balls but permit dust, dirt, chalk and other foreign matter to fall therethrough and not accumulate therein, 45 thereby providing at all times a clean and sanitary pocket free from the objections heretofore mentioned.

The invention is adaptable to tables provided with gullies as well as tables not provided with gullies, and a further object of the invention is to provide means for retaining a ball in a pocket which is connected with a gully so that it may be removed from the pocket by hand or for other purposes.

50 My invention has other objects in view

which will more fully appear in connection with the detail description thereof in connection with the accompanying drawings, in which—

Figure 1 is a plan view of a corner of a 60 pocket-billiard table showing my invention embodied therein in connection with a gully; Fig. 2 is a sectional view on the line 2—2 of Fig. 1; Fig. 3 is a transverse sectional view on the line 3—3 of Fig. 2; Fig. 65 4 is a sectional view on the line 4—4 of Fig. 5; and Fig. 5 is an elevation of my improved pocket applied to a table without a gully. Fig. 6 is a detail view.

Referring to the drawings, 6 is a pocket 70 iron which is fastened to the table by bolts 7 in the usual manner and is provided with the outer and inner finishing and protector strips 8, 9 made of leather or other suitable material.

A plurality of bars 10 arranged in substantially parallel relation and spaced apart are engaged at their upper ends with the strip 11 which is connected with the pocket iron 6 in a suitable manner. This strip 75 11 is preferably made of metal and fastened in a suitable manner to the leather covering 6' on the pocket iron and between the strips 8 and 9, and the bars 10 are hung from said strip in a suitable manner. For 80 example, as shown, the strip may be provided with a tongue 12 to engage an opening 12' at the upper end of the bar and also with lugs 12'' to be bent over the outer rims of the bar to secure the bar rigidly in 85 place. The pocket bars 10 are made of longitudinally corrugated or fluted metal strips 10' having their edges crimped over to hold the rubber or other suitable covering 10'' on the convex side of the bars, 90 and these bars have a substantially right angle bend intermediate of their ends to form the pocket. The upper ends of the bars extend in a substantially vertical direction and are engaged with the strip 11 95 as aforesaid, and the lower ends of the bars extend in a substantially horizontal direction, with a slight decline, into the opening 100 or channel 13 on the table.

In Figs. 1-3 I have shown the pocket 105 embodied in a table provided with a gully, indicated at 14, and which is more fully set forth and described in my companion application Serial No. 27,833, filed May 13, 1915. The lower inner ends of the bars 110

are arranged in the channel 13 in the table and secured to the wall thereof in a suitable manner. For this purpose I may fasten a metal strip 16 to the channel wall and provide it with lugs 16' to be bent over the rims of the bars to securely hold the bars in place. A brace 17 may be located at the bottom of the bend in the bars and secured in place at its ends by the fastening bolts 7. 16 This brace is bent to engage the bars 10 and assist in holding them in properly spaced relation.

In the construction of Figs. 4 and 5 the ends of the bars may abut against or be engaged with a strip 18 fastened to the table and a brace 19 may also be provided and secured in place by the bolts 7 and shaped to form a support and spacing member for the bars at the bottom of the pocket. 15

20 My improved pocket thus consists essentially of a plurality of substantially parallel bars spaced apart and bent intermediate of their ends, the upper ends being connected with the pocket iron and suspended therebeneath and the lower ends being suitably supported to form the pocket. In the drawings I have shown four bars with the convex rubber covered sides thereof on the inside of the pocket to form a cushion of 25 soft engaging surface for the ball. These bars are spaced apart so that chalk and foreign matter may fall through between the bars while a ball will be retained in the pocket and it will readily be observed 30 that the spacing of the bars is controlled entirely by the diameter of the balls. Any dirt brushed off the table into the pocket or cigar or cigarette ashes or stubs dropped into the pocket will fall through between 35 the bars and not accumulate in the pocket and if, in course of time, the bars do gather a little dust they can be easily brushed or wiped clean with a cloth. The spaces between the bars are large enough to permit 40 the passage of chalk and hence there is no danger of the gully being choked or the passage of the ball therethrough being interfered with by chalk or any other material sliding into the gully from the pocket. 45

50 When my improved pocket is embodied with a gully it may be desirable at times to retain the ball in the pocket temporarily and for this purpose I provide a stop in the channel 16 where the pocket merges into 55 the gully, which can be readily adjusted to operative or inoperative position. In the embodiment of the invention illustrated in the drawings the stop 20 is hinged at 21 to an extension 22 on the strip 16, between 60 the two inner bars of the pocket, but I do not confine myself to this particular construction or arrangement of parts. This stop normally lies above the bottom of the channel between the bars, as shown in Fig. 65 2, but it can be swung into upright posi-

tion, as shown in dotted lines in Fig. 3, to prevent the passage of the ball from the pocket into the gully, as will be readily understood. It will be found an easy matter to insert the hand in the pocket to 70 swing the stop to operative or inoperative position, as may be desired.

My invention is strong and substantial in construction and when once secured in place on the table the pocket is not liable to become disarranged or to get out of order. The curved or fluted metal bars are strong and rigid and will not become displaced under any ordinary usage. This is important because players often hit the pockets 75 with their cues and sometimes subject the pockets to rough usage, but my improved pocket is sufficiently strong to stand any ordinary amount of such abuse. The pocket is constructed so that it can be shipped ready 80 for attachment to the table and it requires no special knowledge or skill for this purpose. The braces 17 and 19 are preferably used in or about the location shown on the drawings to reinforce and strengthen the 85 pocket, but for some purposes at least it may be found unnecessary to employ these braces. It will be understood, of course, that the hinged stop 20 is not a necessary part of the 90 pocket when used with a gully but it can be provided in all pockets, if desired, so that 95 it will be there for use whenever required. This stop does not in any way interfere with the balls when in an inoperative position, as shown in full lines in Fig. 2, being located 100 below the surface on the bottom bars 10 on which the ball travels.

I am aware that changes in the form and proportion of parts and details of construction of my invention may be made without 105 departing therefrom and I therefore reserve the right to make all such changes as fairly fall within the spirit and scope of my invention.

I claim:

1. A pocket for pocket billiard tables comprising a plurality of rigid bars concavo-convex in cross section and adapted to be held in place in spaced relation on a table, said bars having a yielding facing on their 115 convex sides.

2. A pocket for pocket billiard tables comprising a plurality of rigid bars adapted to be held in place in spaced relation on a table, said bars being fluted longitudinally and having their side edges directed outwardly and their intermediate portions directed inwardly of the pocket.

3. A pocket for pocket billiard tables comprising a plurality of bars spaced apart and 125 arranged in substantially parallel relation, and strips engaged with said bars at or adjacent the ends thereof and adapted to be held in place on a table.

4. A pocket for pocket billiard tables com- 130

- prising a metal strip supported on the table, a plurality of bars fastened together in spaced relation, and means for detachably engaging the bars with said strip.
- 5 5. A pocket for pocket billiard tables comprising a metal strip supported on the table, a plurality of bars fastened together in spaced relation, and a hook on the strip to engage a bar to suspend the bars from said 10 strip.
6. A pocket billiard table provided with a gully channel and a pocket, and a movable stop located where said pocket connects with the gully channel and adapted to be arranged in position to prevent balls passing from the pocket into the gully or to permit such passage.
- 15

7. A pocket billiard table provided with a gully channel and a pocket, and a hinged movable stop located where said pocket connects with the gully channel and adapted to be swung into upright position to prevent balls passing from the pocket into the gully.
8. A pocket billiard table provided with a gully channel and a pocket connecting therewith, said pocket comprising a plurality of bars spaced apart and arranged substantially parallel, and a hinged stop located in the gully channel and arranged to be swung into position to prevent passage of balls 30 from the pocket to the channel.

FRANK C. HOBBS.
